VARIABLE DISPLACEMENT FUEL PUMP

James P. Johnson, Shaker Heights, Ohio, assignor, by mesne assignments, to Pump Engineering Service Corporation, Cleveland, Ohio, a corporation of Ohio

Application August 19, 1938, Serial No. 225,659

5 Claims. (Cl. 103—120)

This invention relates to fuel pumps designed particularly for use on aircraft, although not so restricted, and has for its primary object to provide an improved fuel pump of the rotary vane or blade type having a variable displacement but where the discharged fuel is maintained at predetermined constant pressure regardless of volume required by the motor.

It is a further object of the present invention to provide, in a fuel pump of the type referred to, a pressure responsive means actuated by the pressure of the discharged fuel in excess of that predeterminately selected whereby the capacity of the pump may be varied.

15 A further object of the present invention is to provide suitable adjustment whereby the capacity of the pump may be varied between substantially no delivery of fuel and its maximum requirement regardless of the rotor speed.

20 In the prior types of fuel pumps such as illustrated in my copending applications, Serial No. 10,644, filed March 12, 1935, Serial No. 170,844, filed October 25, 1937, and Serial No. 196,693, filed March 18, 1938, the maximum volume of fuel was handled by the pump, the excess over that required by the motor being by-passed back to the inlet side of the pump. It has been found that there are certain objections to by-passing this volume of fuel within the pump in that it 25 tends to increase the temperature of the fuel and additionally, the rotation of the rotor blades in contact with the fuel tends to whip up the latter thereby producing air pockets which may encourage vapor locks at altitudes where this 30 would be objectionable. It is therefore, a further object of the present invention to provide a variable displacement fuel pump which will deliver only that volume of fuel required by the motor regardless of rotor speeds whereby heating and heating of the fuel is eliminated or 35 materially reduced to a negligible amount.

40 Another object of the present invention is to provide an improved and simple means by which the fuel pump may be operated in either direction.

45 A still further object of the present invention is to provide a fuel pump of the type referred to which is simple in construction, efficient in operation and inexpensive to manufacture.

50 With the objects above indicated, and other objects hereinafter explained in view, my invention consists in the construction and combination of elements hereinafter described and claimed.

55 Referring to the drawings,

Figure 1 is an end elevational view of a pump embodying the present invention.

Figure 2 is a top plan view of the pump shown in Figure 1.

Figure 3 is a vertical sectional view taken on line 3—3 in Figure 2 and showing the structural features of the pump.

Figure 4 is a vertical sectional view taken on line 4—4 in Figure 2, and showing in further detail the structural features of the pump.

Figure 5 is a transverse sectional view taken on line 5—5 in Figure 4 and showing details of the structure.

Figure 6 is a transverse sectional view taken on line 6—6 in Figure 3 and showing in detail the upper side of the diaphragm.

Figure 7 is a transverse sectional view taken on line 7—7 in Figure 3 and showing in detail the under side of the diaphragm.

In the drawings, I have illustrated one type 20 of fuel pump embodying the present invention, the structural details of which have been tried and successfully tested, but the invention may be otherwise adapted as will be apparent to those skilled in the art.

The fuel pump comprises a housing generally designated by the numeral 10, preferably consisting of a casting of aluminum or other desirable light weight material. The housing is provided with an axially disposed bore 11 extending inwardly from one end thereof and terminating in a transverse wall 12. The housing 10 is further provided with an integral portion 13 of reduced diameter which extends outwardly and axially of the bore 11, the portion 13 being provided at its outer end with a laterally extending flange 14 by means of which the pump may be suitably attached to the motor or other driving means. The portion 13 has an axially disposed opening 15 communicating at one end with the bore 11 and at its opposite end with an interiorly screw-threaded bore 16 of larger diameter which extends inwardly from the flange 14 providing an abutment or seat 17. The housing 10 is also provided with a pair of outwardly projecting bosses 18 on diametrically opposite sides thereof which are provided with interiorly screw-threaded pipe tap openings 19 and 20 communicating with the bore 11. These openings 19 and 20 function as fuel inlet and outlet openings 50 and are adapted for connection with the fuel supply tank and carburetor respectively.

A bushing 21 of bronze or other suitable material is rigidly mounted within the housing 10 and comprises a tubular portion 22 disposed within 55

the opening 15 and a laterally extending peripheral flange 23 in abutting engagement with the wall 12 and the adjacent peripheral surface of the bore 11, the inner face of the flange 23 being smooth and flat and providing one end wall of the pumping chamber. An outer sleeve or liner 24, of bronze or other suitable material, is rigidly secured within the bore 11 and has one end in abutting engagement with the inner face of the flange 23. The sleeve 24 has a circular opening 25 extending therethrough, the axis of which is eccentric to, slightly below but parallel with the axis of the bore 11, as more clearly shown in Figure 4. The sleeve 24 is further provided with one or more openings 26 and 27 which extend transversely through the wall thereof on diametrically opposite sides in communication with the inlet and outlet openings 19 and 20 respectively. An inner cylindrical sleeve 28, of steel or other suitable material, has a smaller outside diameter than the diameter of the opening 25 in the outer sleeve 24 and is disposed within the latter for relative adjustment for a purpose to be later described. The sleeve 28 abuts at one end with the inner face of the flange 23 and its outer end aligns with the outer end of the outer sleeve 24, as more clearly shown in Figure 3. The inner peripheral surface of the inner sleeve 28 forms the outer wall of the pump chamber and one or more openings 29 and 30 extend transversely through the wall thereof on diametrically opposite sides in communication and preferably in alignment with the openings 26 and 27 respectively in the outer sleeve 24. A cover plate 31 has a circular portion 32 adapted to fit snugly within the open end of the bore 11 and a lateral flange 33 detachably engageable with the adjacent portion of the housing 10. A rubber gasket 34 is disposed between the flange and housing to provide a seal and a plurality of machine screws 35 project through openings in the flange 33 and are secured in screwthreaded aligned openings in the housing. The cover plate 31 is further provided with an axial bore 36 on its inner side in axial alignment with and of the same diameter as the opening 15 in the portion 13 of the housing. A bushing 37, of bronze or other suitable material, and similar to the bushing 21, is securely mounted on the cover plate and has a cylindrical extension 38 disposed within the bore 36 and a laterally extending circular flange 39 on the inside of the portion 32. The inner face of the flange 39 is flat and smooth, in parallelism with the face of the flange 23 and engages the outer ends of the outer sleeve 24 and inner sleeve 28 to maintain them in assembled relation.

A rotor 40, of steel or other suitable material, is rotatably mounted in the housing and comprises a circular body portion 41 of smaller diameter than the inner diameter of said inner sleeve 28 within which the body portion is eccentrically disposed and outwardly projecting axial extensions 42 and 43 which are rotatably mounted in the adjacent bushing extensions 22 and 38 respectively. The rotor is further provided with an axial opening 44 of substantial diameter which extends entirely through the extensions 42 and 43 and body portion 41 within which a tubular roller member 45 is freely disposed. The body portion 41 of the rotor is provided with a plurality of radially disposed slots 46 which extend longitudinally throughout its length and within which are slidably mounted a plurality of blades or vanes 47, the outer ends of which have running engagement with the inner peripheral sur-

face of the inner sleeve while the opposite ends have running engagement with the adjacent faces of the flanges 23 and 39 respectively. The inner ends of the blades 47 project into the opening 44 within the body 41 and are engageable with the roller member 45 which maintains the blades in their proper running position. Six blades are here shown which improve the evenness of flow of the discharged fuel but any other number may be employed to advantage.

In order that the capacity of the pump may be varied the inner sleeve 28 is made adjustable for this purpose. The sleeve 28 is provided with a pair of radial integral projections 48 and 49 on diametrically opposite sides which slidably fit within complementary grooves 50 and 51 formed upon the inner wall of the outer sleeve 24, as more clearly shown in Figure 4. The grooves are of sufficient depth to permit the required movement of the inner sleeve to vary the capacity of the pump from its minimum to its maximum requirements. The sleeve 28 may be predeterminedly positioned and limited in its movement in one direction by means of a machine screw 52 which is threaded through a screwthreaded opening in the housing 10 and its inner end projecting through an aligned opening in the outer sleeve into engagement with the adjacent end of the projection 48, shims 53 being used to obtain the proper adjustment. The axis of the opening 25 in the outer sleeve 24 is fixed as is the axis of the rotor 40, these axes being relatively eccentric but in a common vertical plane, as shown in Figure 4. The axis of the inner sleeve 28 is likewise in the same vertical plane as the aforesaid axes but its relative position varies by reason of the restricted movement of the inner sleeve 28 to positions in engagement with the inner peripheral wall of the outer sleeve at diametrically opposite points and any position therebetween. The relative positions of the various parts shown in Figure 4, effect the maximum capacity of the pump in which the portion 41 of the rotor 40 has a close running engagement with the inner peripheral wall of the inner sleeve 28 at its upper portion. By increasing this clearance the capacity of the pump is lowered and may be decreased to zero or by moving the inner sleeve to its uppermost position, wherein the portion 41 of the rotor 40 has a close running fit with the inner peripheral surface in which position a diametrically opposite slight pressure is created in the direction of the inlet side of the pump. In other words any desired exact volume of fuel may be obtained by the adjustment provided for by the adjustment of this inner sleeve.

The adjustment of this inner sleeve may be accomplished in any desirable manner but preferably by means of fluid pressure as shown in the drawings. The housing 10 is further provided with a second integral laterally extending portion 54 terminating in a dish shaped portion 55 having a marginal flange 56 the upper surface of which provides a seat. The portion 54 is provided with an axial opening 57 within which a tubular plunger or stem 58 is slidably disposed. The lower end of the stem is closed and formed with a reduced portion 59 which projects freely through an aligned opening in the outer sleeve 24. The extreme lower end 60 of the stem is exteriorly screwthreaded and securely threaded into an aligned screwthreaded opening in the projection 49 on the inner sleeve 28 by means of which the latter may be moved. The stem is further provided with a lateral flange 61 extend-

ing circumferentially thereabout and positioned outwardly of the dish shaped portion 55, the stem being exteriorly screwthreaded therebeyond. A disc 62, preferably of steel, has an axial opening fitting over the outer end of the stem and resting upon the outer side of the flange 61 and within the dish shaped portion but spaced therefrom. The disc should be as large as possible so as to be more sensitive to the pressure which actuates it and its outer marginal edge may be turned downwardly at 63. A flat flexible diaphragm 64, preferably of rubber and fabric composition, is disposed above the disc 62 and has an opening through which the stem projects 10

15 The marginal edge portion of the diaphragm 64 rests upon the seat of the flange 56 and is securely clamped by a marginal flange 65 on a cover member 66. The cover member 66 is detachable by means of a plurality of machine screws 67 which extend through aligned openings provided in the flanges 56 and 65 and the adjacent portion of the diaphragm and which screws are threadably secured in the flange 56 to provide a sealed joint. A disc 68, of steel or other 20

25 suitable material, is positioned upon the outer side of the diaphragm 64, and has a diameter slightly greater than that of the disc 62 but not as great as the exposed marginal portion of the diaphragm. The outer edge of the disc 68 may be turned outwardly at 69 to provide a rounded corner for engagement with the diaphragm to prevent injury to the latter and the disc has an axial opening through which the outer end of the stem projects. A nut 70 is screwed onto the 30

35 outer end of the stem into rigid engagement with the disc 68 for securely maintaining the discs and diaphragm in assembled unitary relation and in abutment with the flange 61.

To permit discharge of the fuel at a predetermined selected pressure and to thereafter maintain a constant pressure of the discharged fuel, a coiled spring 71 is used which has a portion disposed within the tubular stem 58 with its lower end in engagement with the closed end of the stem. The upper end of the spring 71 projects beyond the stem and is freely disposed within an axial interiorly screwthreaded opening 72 provided in an extension 73 of reduced diameter formed integrally on the outer side of the cover member 66. An exteriorly screwthreaded plug 74 is threadably mounted in the opening 72 and engageable with the outer end of the spring 71 for tensioning the latter to thereby exert a pressure upon the closed end of the stem whereby the inner sleeve 28 is 40

45 yieldably maintained in its lowermost position. Any means may be employed for adjusting the plug axially within its opening but a simple means embodies a thumb knob 75 having a lateral flange 76 adapted to engage the outer end of the extension 73 and a depending non-circular stem 77 projecting freely through a complementary non-circular opening provided in the plug 74. Thus by turning the knob the plug may be threaded inwardly or outwardly as desired until the spring 50

55 is properly tensioned. The adjustment may be maintained by a bonnet-like nut 78 having an opening through which the knob projects and threaded upon the extension 73 into clamping engagement with the flange 76 on the adjusting member. The upper side of the diaphragm 64 is in communication with the atmosphere through a small opening 79 in a plug 80 which is exteriorly screwthreaded and threadably removably in a screwthreaded opening provided in the cover member 66. In some instances it is desirable to

connect the upper side of the diaphragm with the supercharger in which event the plug 80 is removed and a pipe line is connected therefrom.

As heretofore stated a further important function of the pump is to deliver any volume of fuel required by the motor regardless of rotor speed and while this is accomplished mechanically by means of the movable inner sleeve the movement of the latter is automatically effected by the pressure of the discharged fuel in excess of that desired. The housing 10 is therefore, provided with a passageway 82 which has one end in communication with the discharge side of the pump, or outlet opening 20 and its other end in communication with the under side of the diaphragm 64. To render the pump operable in either direction, a second passageway 83, similar to the passageway 82, is provided in the opposite side of the housing 10 and has one end in communication with the inlet side of the pump or inlet opening 19 and its other end in communication with the under side of the diaphragm. With this adaptation one of the passageways must be closed depending upon the direction of rotation of the rotor. With the rotor rotating in a clockwise direction as shown in Figure 4 the passageway 83 is closed and any suitable means may be employed. However, a simple and efficient means consists in the provision of diametrically disposed bores 84 and 85 which extend inwardly from opposite sides communicating with the passageways 82 and 83 respectively. Inserts 86 and 87 fit snugly within but are removable from the bores 82 and 83 and the insert 86 is provided with a reduced portion 88 adjacent the passageway 82 to permit unrestricted flow of fuel through the latter. The outer ends of the bores are interiorly screwthreaded and plugs 89 are removably mounted therein to prevent accidental displacement of the inserts, the latter being provided on opposite ends with interiorly screwthreaded openings of which the inserts may be removed by the use of a suitable implement. Furthermore the bores and inserts are of identical size so that in order to change the direction of operation of the pump only the position of the inserts are reversed from that shown in Figure 4.

The rotor may be driven by any suitable means but preferably as shown in Figures 3 and 5. A drive shaft 90 is disposed concentrically of the axis of the rotor and has a circumferential flange 91 rotatably mounted in the adjacent end of the bushing extension 22. The shaft is further provided with a tongue 92 on its inner end which extends transversely and projects into aligned complementary recesses in the adjacent end of the rotor extension 42 for imparting rotation to the rotor. The outer end of the shaft 90 projects outwardly beyond the attaching flange 14 and is provided with splines 93 adapted for operative connection with the motor or other power source. A retainer member 94, preferably of aluminum material, is exteriorly screwthreaded at its outer portion and removably mounted in the threaded bore 16 adjacent the flange 14. The retainer member 94 also has a portion 95 of reduced diameter which terminates in a lateral flange 96 in abutting relation with the seat 17. A gasket 97 is disposed between the flange 96 and the seat 17 to provide an effective seal against the escape of oil. The inner end of the retainer member 94 is further provided with an axial bore 98 communicating at its inner end with an axial bore 99 of slightly smaller diameter providing an axially disposed flange 100 extending circumferentially 70

75

about the adjacent portion of the shaft. A metal seal disc 101 is mounted within the bore 98 for slight axial movement and in abutting engagement with the adjacent end of the flange 91, the 5 opposite side being in spaced relation to the bottom of the bore 98. A resilient seal ring 102 of rubber and fabric composition, is disposed within the bore 99 the opposite sides abutting the bottom of the bore and the ring respectively and 10 encircling the flange 100. This construction provides a yieldable seal against the leakage of oil. The retainer member 94 is further provided with a cored chamber 103 encircling the shaft and passageways 104 providing communication between 15 the chamber and the reduced portion 95 at diametrically opposite sides as more clearly shown in Figure 5. A plurality of radially disposed passageways 105 are provided in the extended portions 13 of the housing which communicate at 20 one end with the reduced portion 95 of the retainer member and at their other end with pipe tapered openings 106 normally closed by means of screwthreaded plugs 107. These communicating passageways are provided so that any oil which 25 is taken up by the drive shaft and released by rotation will be led away from the pump elements and may be drained off by the removal of one of the plugs 107. The retainer member 94 is normally maintained in proper position by 30 means of a bolt 108.

The oil seal is effectively maintained by the pressure created in the pump which exerts an outward force upon the flanged end of the shaft 90 and consequently the disc 101 thus compressing the ring 102. In the event that there is insufficient pressure within the pump, as in starting etc., the seal is nevertheless normally effective by utilizing the tubular roller member 45 as more clearly shown in Figure 3. The closed end of 35 the roller member 45 abuts the adjacent end of the tongue 92 on the shaft 90. A coiled spring 109 is disposed within the roller member and has one end in engagement with the closed end thereof while its other end engages a pin 110 40 slidably mounted in the open end of the roller member. The pin 110 has a portion projecting outwardly terminating in a head 111 which abuts the bottom of the bore 36. This spring 109 may be predeterminedly selected so as to exert 45 the desired pressure on the closed end of the roller member which in turn suitably compresses the ring to prevent leakage.

In the operation of the pump, with the elements in their relative position shown in the drawings 50 and the rotor being driven, by the motor, in a clockwise direction as indicated by the arrows in Figure 4, the inlet opening 19 is connected with the fuel supply tank and the outlet opening 20 is connected with the carburetor which in turn 55 is connected with the motor in a manner well known. As before stated the fuel discharged by the pump should be at a constant pressure regardless of the volume required and consumed by the motor and this discharge pressure is effected 60 and maintained by predeterminedly tensioning the spring 71 in the manner heretofore described. As the rotor rotates, fuel is drawn in at the inlet opening due to the created suction, and picked up by the blades which in turn conveys the fuel 65 65 around the pump chamber to the outlet side where the fuel is discharged under pressure through the outlet opening 20 in a manner well known.

It will be understood, of course, that the capacity of the pump varies almost in direct propor-

tion to the R. P. M. of the rotor where close clearances and tolerances are maintained, and consequently the pump would, under ordinary circumstances, be required to handle a volume of fuel greatly in excess of that required by the motor, 5 as will be more apparent from a study of my copending applications heretofore referred to. To maintain the relation between fuel consumed by the motor and fuel handled by the pump, any increase in pressure of the discharged fuel in 10 excess of that desired, is transmitted to the under side of the diaphragm 64 and disc 62 causing the latter to be raised and with it the inner movable sleeve 28 in opposition to the tensioned spring 71. This movement of the sleeve 28 increases the running clearances between the body portion 41 of 15 the rotor and the upper inner peripheral surface of the sleeve 28, as viewed from Figure 4, thereby reducing the capacity of the pump to a point where the volume of fuel handled thereby is substantially equal to that required by the motor regardless of the rotor speed. As the maximum displacement of the pump is many times greater than the required displacement, the screw 52 is provided for predeterminedly effecting the minimum running clearance between the body portion 41 of the rotor and the inner peripheral surface of the sleeve 28. This automatic operation is made possible by closing off the passageway 83 by means of the removable insert 87 and the 20 pump may be operated in a reverse direction by merely interchanging the inserts 86 and 87 from their relative positions as shown in Figure 4.

While I have described the preferred embodiment of the invention it is to be understood that I am not to be limited thereto inasmuch as changes and modifications may be resorted to without departing from the spirit of the invention as defined in the appended claims.

What is claimed is:

1. In a variable displacement fuel pump for aircraft, a housing having fuel inlet and outlet openings, a sleeve movably mounted in said housing, having a circular opening extending therethrough and additional openings for cooperation with said inlet and outlet openings, a rotor rotatably mounted in said housing about a fixed axis eccentric to the axis of said circular opening and positioned within said sleeve and having a portion normally in running engagement with the inner peripheral surface of said circular opening, said rotor having reciprocal blades adapted for drawing fuel into the inlet opening and discharging the same under pressure from the outlet opening, means in said housing sensitive to minute variations through a wide range of changes in surrounding atmospheric pressures for adjusting said sleeve to vary the eccentricity of said rotor relative to said sleeve in response to changing surrounding atmospheric pressures whereby to cause said pump to deliver a constant pressure at said outlet opening irrespective of said changing pressures, said means including a flexible disc-like diaphragm in communication on the outer side thereof with the atmosphere through a small opening formed in said housing and in communication on the inner side thereof with said outlet opening, whereby outlet fluid pressure acts to urge said sleeve in the direction of least eccentricity, and resilient means for urging said sleeve in the direction of greatest eccentricity with a predetermined force.
2. In a pump adapted for supplying fuel to the charge-forming device of an aircraft said pump being capable of delivering said fuel at a con-

stant delivery pressure irrespective of varying inlet pressures said pump comprising a housing having fuel inlet and outlet openings, a sleeve formed with a circular opening therethrough mounted in said housing for adjustment transversely to the axis of said circular opening said sleeve being formed with additional openings for cooperation with said inlet and outlet openings, a rotor rotatably mounted in said circular opening about a fixed axis, said rotor having reciprocal blades carried thereby arranged for drawing fuel from said inlet opening and for discharging the same from said outlet opening, means in said housing being sensitive to minute variations through a wide range in surrounding atmospheric pressures for adjusting said sleeve relative to said rotor to vary the eccentric relation between the axis of said rotor and the axis of said sleeve for varying the difference between said inlet and said delivery pressures, said means comprising a flexible disc-like diaphragm sealably connected at its periphery with said housing and provided with means connecting the central portion thereof with said sleeve, said housing being formed with a passage placing the underside of said diaphragm in communication with said pump outlet and with a second passage of smaller size placing the upper side of said diaphragm in communication with the atmosphere and means for urging said sleeve in the direction of its greatest eccentricity relative to said rotor with a predetermined force, whereby the surrounding atmospheric pressure changes are made to affect the upper side of the diaphragm thus causing said eccentricity varying means to vary said eccentricity to produce a constant delivery pressure.

3. In a variable displacement fuel pump for aircraft, a housing having fuel inlet and outlet openings, a sleeve movably mounted in said housing and having a circular opening extending therethrough, said sleeve being formed with additional openings therethrough for cooperation with said inlet and said outlet openings respectively, a rotor rotatably mounted in said housing about a fixed axis eccentric to the axis of said circular opening and positioned within said sleeve and having a portion normally in running engagement with the inner peripheral surface of said circular opening, said rotor having reciprocal blades adapted for drawing fuel into the inlet opening and discharging the same under pressure from the outlet opening, means in said housing connected to said sleeve effective to adjust the same to vary the eccentricity thereof relative to said rotor, comprising resilient means for urging said sleeve in the direction of greatest eccentricity with a predetermined force, means defining a chamber adjacent said rotor pumping means, means including a flexible disc-like diaphragm dividing said chamber into a first compartment and a second compartment, a threaded opening in the wall of said second compartment adapted to be placed in communication with a source of variable fluid pressure, a first passage formed in said housing adapted to place said first compartment in communication with said pump outlet, a second passage formed in said housing adapted to place said first compartment in communication with said pump inlet, threaded openings formed in said housing and intersecting each of said passages, a first threaded closure means arranged to fit each of said last named threaded openings and permitting flow thereby through the associated passage, a second threaded closure means arranged to fit each of said last named threaded

openings and effective to shut off flow through the associated passage, whereby the direction of operation of said pump may be reversed merely by interchanging said threaded closure means, and constant delivery pressure is obtained irrespective of the direction of operation of said pump.

4. In a variable displacement fuel pump for aircraft, a housing having fuel inlet and outlet openings, a sleeve movably mounted in said housing having a generally circular opening extending therethrough and having additional openings for cooperation with said inlet and outlet openings, a rotor rotatably mounted in said housing about a fixed axis normally eccentric to the axis of said circular opening and positioned within said sleeve and having a portion normally in close running association with the inner peripheral surface of said sleeve, said rotor having reciprocal blades adapted for drawing fuel into the inlet opening and discharging the same under pressure from the outlet opening, means in said housing sensitive to minute variations through a wide range of changes in surrounding atmospheric pressures for adjusting said sleeve to vary the eccentricity of said rotor relative to said sleeve in response to changing surrounding atmospheric pressures whereby to cause said pump to deliver a constant pressure to said outlet opening irrespective of said changing pressures, said means including a flexible disc-like diaphragm and means placing the same in communication on one side thereof, at least indirectly, with the atmosphere and in communication on the other side thereof with said outlet opening, whereby outlet fluid pressure acts to urge said sleeve in the direction of least eccentricity and resilient means for urging said sleeve in the direction of greatest eccentricity with a predetermined force, said arrangement being further particularly characterized by the provision of a hollow stem passing through the central portion of said diaphragm and closed at the lower end thereof and connecting said sleeve with said diaphragm, said resilient means comprising a long helical spring positioned within said stem and engaging said closed end thereof and means engaging the other end of said spring above said diaphragm for adjusting the compression thereof.

5. In a variable displacement fuel pump for air craft, a housing having fuel inlet and outlet openings, a sleeve movably mounted in said housing having a generally circular opening extending therethrough and additional openings for cooperation with said inlet and outlet openings, a rotor rotatably mounted in said housing about a fixed axis normally eccentric to the axis of said circular opening and positioned within said sleeve and having a portion normally in close running association with the inner peripheral surface of said circular opening, said rotor having reciprocal blades adapted for drawing fuel into the inlet opening and discharging the same under pressure from the outlet opening, means in said housing connected to said sleeve effective to adjust the same to vary the eccentricity thereof relative to said rotor, said means comprising means defining a chamber adjacent said rotor pumping means, means including a flexible disc-like diaphragm connected to said sleeve and dividing said chamber into a first compartment and a second compartment, an opening formed in the wall of said second compartment adapted to communicate with a supercharger outlet, means defining a passage placing said first compartment and the

adjacent side of said diaphragm in communication with said pump outlet, whereby said pump outlet fluid pressure acts to urge said sleeve in the direction of least eccentricity, a sensitive resilient means arranged to urge said sleeve in the direction of greatest eccentricity with a predeter-

mined force, said arrangement being sensitive to minute variations through a wide range of changes in the pressures to which said diaphragm is subjected.

JAMES P. JOHNSON. 5
